UNITED STATES PATENT OFFICE.

HENRY ALBERT CUTLER, OF BELFAST, IRELAND.

MEANS FOR REMOVING DEPOSIT FROM DRAINS, PIPES, AND THE LIKE.

1,262,755.

Specification of Letters Patent. Patented Apr. 16, 1918.

Application filed March 27, 1917. Serial No. 157,803.

To all whom it may concern:

Be it known that I, HENRY ALBERT CUTLER, a subject of the King of Great Britain and Ireland, residing at Belfast, in the 5 county of Antrim, Ireland, have invented Improvements in or Relating to Means for Removing Deposit from Drains, Pipes, and the like, of which the following is a specification.

10 This invention relates to scraper arrangements for removing deposit from drains, pipes and the like of the kind comprising a single blade so hinged to a drawbar or equivalent that on moving the arrangement 15 into position for use the blade is caused to assume an inoperative position and on withdrawing the arrangement the blade is caused to assume its operative position.

Arrangements of the kind specified form 20 the subject of application for Letters Patent granted to me, Serial No. 98,385, filed 18th May, 1916, the specification whereof describes examples wherein lines provided for moving the drawbar and blade or scraper 25 alternately in opposite directions actuate position controlling means adapted to cause the scraper to fall down against the drawbar or take up an operative position according to the direction in which the lines are moved.

30 The present invention has for object to provide simple and efficacious means whereby for instance the apparatus is rendered conveniently applicable to ordinary drain rods and for pipes, drains and the like of 35 relatively small cross-sectional area.

For this purpose a device according to the invention comprises a drawbar provided with a forwardly extending supplementary portion on which the blade is pivotally 40 mounted and which is capable by the act of moving the device inwardly or outwardly of a pipe of sliding longitudinally relatively to the rearwardly extending main portion of the drawbar, the two portions coacting with 45 connecting means that serve to move the blade into its inoperative or operative positions respectively.

The invention can be carried into effect in 50 various ways, one example whereof, applicable for attachment to a drain rod, is illustrated in the accompanying drawings wherein:

Figure 1 is a plan and Fig. 2 a side elevation of a device according to the invention

showing the blade in its closed or inoperative position and Fig. 3 a view corresponding to Fig. 2 but showing the blade in its open or operative position.

According to this example the rearward portion *a* of the drawbar constitutes a sleeve 60 adapted to so receive the inner end of the forward portion *c* carrying the blade *d* that the portion *c* can be freely reciprocated therein, the interconnection between the portions *a* and *c* being effected by a link *e* pivoted at or near the circumference of the blade *d* to a lug *f* thereon and at its other end to a lug *g* on the sleeve constituting the rearward portion *a* of the drawbar. The arrangement is such that pressure from the 70 rear, as through the drain rod *b*, when inserting the device into a pipe, will cause the portion *a* to slide forwardly along the companion portion *c*, thus reducing the longitudinal distance between their forward ends 75 thereby causing the blade *d* to assume its inoperative position (Figs. 1 and 2). Conversely, upon pulling the drain rod *b* in the opposite direction the said longitudinal distance between the portions *a* and *c* will be 80 increased and the blade *d* thereby brought into operative position, (Fig. 3).

To limit the relative movement between the portions *a* and *c* according to requirement, one thereof, may be formed with a 85 longitudinal slot or slots having a length corresponding with the required degree of travel and the other portion with a pin or pins projecting into the slot or slots. In the example the portion *c* is formed with a longitudinal slot *h* and the other portion *a* with a pin conveniently a set screw *j*, that projects into the slot.

For attaching the device to the drain rod in such manner that rotation of either about 95 its axis shall not involve rotation of the other, a swivel or like joint is interposed between the portion *a* of the drawbar and the drain rod. Such jointing means may comprise, as in the example, a pair of blocks *k* 100 and *l* or equivalent, slightly spaced apart one in front of the other, one end of the block *k* having the portion *a* secured therein and the farther end of the block *l* being secured as by a threaded part *m* to the correspondingly threaded drain rod, the two 105 being connected through alined longitudinal perforations *n* and *o* by a bolt *p* about the

shank of which the block *k* and the drawbar can freely rotate relatively to the block *l* and the drain rod.

What I claim is:—

- 5 1. Means of the kind described comprising a draw-bar composed of a forwardly extending longitudinally movable supplementary member and a rearwardly extending main member, a blade pivoted intermediate 10 of its width on said supplementary member, adapted when moved into its operative position to substantially fit the bore of the drain pipe or the like to be cleaned, means connecting the blade and the rearwardly extending main member of said drawbar, said means coacting, upon moving the device inwardly or outwardly of a pipe, with the blade and the rearwardly extending main member to effect a longitudinal movement 15 of the supplementary member relatively to the main member and simultaneously to rotate the blade into an inoperative or operative position according to the direction of movement.
- 10 2. Means of the kind described comprising a drawbar composed of a forwardly extending supplementary member offset intermediately of its ends and a rearwardly extending main member, a blade, pivoted on 20 said supplementary member at its offset portion, a lug on the blade, a corresponding lug on the main member and a link connecting said lugs, said link coacting with the main and supplementary members to effect a longitudinal movement of the supplementary member to move the blade into an inoperative or operative position according to the direction of movement.
- 25 3. Means of the kind described comprising a drawbar composed of a forwardly extending supplementary member and a rearwardly extending main member, a blade pivoted on said supplementary member, means connecting said blade and the main 30 member, said means coacting with the blade and the rearwardly extending main member to move the blade into an inoperative or operative position as required, a drain rod fitting and connecting means between the rearwardly extending main member and said drain rod fitting adapted to prevent rotation of either causing rotation of the other.
- 35 4. Means of the kind described comprising a drawbar composed of a forwardly extending supplementary member and a rearwardly extending main member, a blade pivoted on said supplementary member, means connecting said blade and the main member, said means coacting with the blade and the rearwardly extending main member to move the blade into an inoperative or operative position as required, a drain rod fitting and a swivel device connecting the rearwardly extending member and the drain rod fitting.
- 40 5. Means of the kind described comprising a drawbar composed of a forwardly extending supplementary member and a rearwardly extending main member, a blade pivoted on said supplementary member, means connecting said blade and the main member, said means coacting with the blade and the rearwardly extending main member to move the blade into an inoperative or operative position as required, a bolt carried on the rearwardly extending main member, the head of said bolt being rotatably seated therein and a drain rod fitting secured to the shank of said bolt and adapted for attachment to a drain rod.

Signed at City Hall Belfast this twenty-first day of February, 1917.

HENRY ALBERT CUTLER.
